BED LAMP

Jack Galter, Chicago, Ill., assignor to Victor Nemoroff, Chicago, Ill.

Application February 19, 1941, Serial No. 379,649

2 Claims. (Cl. 240—4)

My invention relates to a lamp adapted to be attached to a bed.

Among the objects of my invention is to provide a lamp having a construction for positioning the light providing means within the casing and for also attaching the lamp to a bed; to create means for attaching the lamp to the bed which will contact the bed at the fewest possible places and which will not scratch the bed; to supply a construction for firmly positioning the lighting means within the casing so that there will be no disconnection due to vibration and which will furnish maximum reading illumination; to provide a construction of maximum simplicity with a minimum of parts; to furnish a bed lamp economical in original cost and upkeep, simple to install or remove, and lasting in wear, and such other objects, advantages, and capabilities as will later more fully appear and which are inherently possessed by my invention.

While I have shown in the accompanying drawings a preferred form of my invention, yet I desire it understood that the same is susceptible of modification and change without departing from the spirit of my invention.

Referring to the drawings, Fig. 1 is a front elevational view; Fig. 2 is a top plan view; Fig. 3 is a rear elevational view; Fig. 4 is an end elevational view and Fig. 5 is a rear elevational view of my bed lamp; Fig. 6 is a longitudinal sectional view on line 6—6 of Fig. 1; Fig. 7 is a plan view of the panel assembly, and Fig. 8 is a detailed sectional view on line 8—8 of Fig. 1.

The embodiment selected to illustrate my invention comprises a casing 10 of Bakelite, plastic or other suitable material, having an opening 11 in its front portion. A frame 12 surrounds said opening 11 on the inside of the casing 10 and has a pair of inwardly projecting portions 13 extending from each side of the frame 12 into the opening 11. A translucent member 14 is positioned to cover said opening 11 with the inner side portions of said translucent member contacting the outer portions of said extensions 13 and the outer top and bottom portions of said translucent member extending beyond the corresponding portions of the frame 12 and contacting the inner surfaces of the top and bottom portions of the housing 10. The casing 10 has an open back portion 15. At each of the inner opposite ends of the casing 10 is a boss 16 having a screw threaded opening 17.

A metal panel 18 has a main central body 55

portion 19, a pair of integral raised portions 20, one on each side of said central portion 19, a pair of integral end portions 21, one on each side of said raised portions 20, and a pair of extensions 22, one on the outer end of each of said end portions 21. Each extension 22 has an opening 23 therethrough.

Attached to the inner surface of one of said end portions 21 is one portion of a right angle bracket 24. The other portion of the bracket 24 supports an inwardly extending electric light socket 25 adapted to hold an electric light bulb.

The panel 18 is attached to the housing 10 by placing the inner surfaces of the extensions 22 against the bosses 16, and by means of screws 26 extending through openings 23 in extensions 22 and into screw threaded openings 17 in bosses 16. The ends of extensions 22 may be extended to bear against the inner surface of the end walls of housing 10 to hold panel 18 in position by friction grip.

A pair of clamping members 27 have their inner portions 28 attached to the inner surfaces of raised portions 20, and have integral hook portions 29 bent back below the outer surfaces of raised portions 20. A tubing 30 of rubber or the like is placed to cover hook portions 29. On the outer surfaces of raised portions 20 are attached felt members 31 to cooperate with the rubber tubing 30 on the clamping portions to prevent scratching of the bed to which the bed lamp is to be attached.

An electric light cord leads from socket 25 through an opening 32 in bracket 24 and opening 33 in end portion 21 of panel 18 to an electrical source of supply.

A switch has a connection 34 leading from the socket 25 rearwardly through opening 35 in the bottom portion of casing 10, with a manually operable knob 36 at the exterior of the casing.

Having thus described my invention, I claim:

1. A bed lamp comprising a casing having an opening in its front portion and an open back portion, a removable translucent member attached to said casing and covering said opening in its front portion, a thin panel having a flat body portion of sufficient size to substantially cover the open back portion of said casing, said casing having therein a pair of inwardly extending spaced bosses at its opposite side portions, said bosses extending rearwardly within said casing and ending a distance short of the edges of said casing substantially equal to the width of said panel, said bosses having screw threaded openings at their rear ends, said panel

having a pair of outwardly extending end portions integral with and of smaller size than said body portion, said end portions being flat and on the same plane as the body portion of said panel the inner surfaces of said end portions positioned to contact the spaced bosses at opposite side portions of said casing so that the outer surface of said panel lies substantially flush with the edges of said casing, removable screw threaded members extending forwardly through said end portions into the screw threaded openings of said bosses for attaching the end portions to said bosses, an electric light socket adapted to hold an electric light bulb positioned within said casing and attached to the inner surface of said panel, an electric light cord leading from said electric light socket extending through said panel and adapted to be attached to an electrical source of supply, and bracket members attached to said panel and having hook portions adapted to engage a bed.

5 2. A bed lamp comprising a casing having a window in its front portion and an open back portion, said casing having therein a pair of substantially deep, threaded, spaced bosses at its side portions, a panel having a flat body portion and flat end portions on the same plane as said body portion, said panel extending across the open back portion of said casing, the end portions of said panel positioned against the outer ends of said bosses and lying substantially flush with the open back portion of said casing, removable members extending forwardly through the end portions of said panel and threaded into said bosses for attaching said panel to said casing, lighting means positioned within said casing and attached to said panel, and means attached to said panel for removably attaching the lamp to a bed.

JACK GALTER.
